(57) CLAIM

The ornamental design for a tie down noseband, as shown and described.

DESCRIPTION

FIG. 1 is a left side view of a tie down noseband according to my new design as appearing on a horse's head.

FIG. 2 is a right side view of the tie down noseband of FIG. 1 as appearing on a horse.

FIG. 3 is a left side view of the tie down noseband without the horse's head.

FIG. 4 is a right side view of the tie down noseband without the horse's head.

FIG. 5 is a front perspective view of the tie down noseband. FIG. 6 is a rear perspective view of the tie down noseband. FIG. 7 is a bottom perspective view of the tie down noseband; and,

FIG. 8 is a top perspective view of the tie down noseband. The broken line showing of a horse head in FIGS. 1-2 and attached rope in FIGS. 1-4 depict environmental subject matter and forms no part of the claimed design. All remaining broken lines in FIGS. 1-8 depict portions of the tie-down noseband that form no part of the claimed design.
